Search Report for Taiwanese Application No. 099303307 dated Oct. 3, 2011.

Primary Examiner — Paula Allen Greene*(74) Attorney, Agent, or Firm* — Sterne, Kessler, Goldstein & Fox P.L.L.C.(57) **CLAIM**

The ornamental design for an audio listening system, as shown and described.

DESCRIPTION

FIG. 1 is a front perspective view of an audio listening system showing the claimed design;

FIG. 2 is a rear view thereof;

FIG. 3 is a front view thereof;

FIG. 4 is a left side perspective view thereof;

FIG. 5 is a left side view thereof; and,

FIG. 6 is a right side view thereof.
